Des. 228,773
Patented Oct. 23, 1973

228,773

SKILL GAME CABINET

Jonathan W. Amy, West Lafayette, Ind., John H. Beynon, Buxton, England, and David O. Jones, Seattle, Wash., assignors to Analog and Digital Controls Corporation, West Lafayette, Ind.

Filed Aug. 11, 1971, Ser. No. 171,036

Term of patent 14 years

Int. Cl. D21—01
U.S. Cl. D34—5 J

Fig. 1.

Fig. 2.

Fig. 3.

FIG. 1 is a top plan view of a skill game cabinet showing our new design.

FIG. 2 is a side elevational view thereof.

FIG. 3 is an end elevational view thereof.

The opposite side is a mirror image of that shown in FIG. 2 and the opposite end is a mirror image of that shown in FIG. 3. The bottom is without ornamentation.

We claim:

The ornamental design for a skill game cabinet, as shown and described.
